Des. 199,345
Patented Oct. 6, 1964

199,345

ASH TRAY

Oscar A. Hofmeister, Park Ridge, Stevens Point, Wis.

Filed Sept. 11, 1963, Ser. No. 76,556

Term of patent 14 years

(Cl. D85—2)

FIG. 1 is a perspective view of an ash tray showing my new design;

FIG. 2 is an end view;

FIG. 3 is a side view;

FIG. 4 is a top plan view;

FIG. 5 is a sectional view taken on the line 5-5 of FIG. 4; and

FIG. 6 is a sectional view taken on the line 6-6 of FIG. 4.

I claim:

The ornamental design for an ash tray, substantially as shown.
